PEDAL ORNAMENT

Sid Corlin, Chicago, Ill.
(P.O. Box 8731, Honolulu 15, Hawaii)

Filed Apr. 28, 1965, Ser. No. 85,014

Term of patent 14 years

(Cl. D90—11)

The dotted line showing of the pedal in FIGURE 1 is for illustrative purposes.

I claim:

The ornamental design for a pedal ornament, as shown and described.
